SHEET FEED GUIDE

Gordon P. Taillie, Rochester, N.Y., assignor to Xerox Corporation, Rochester, N.Y., a corporation of New York

Filed Mar. 1, 1962, Ser. No. 176,528
3 Claims. (Cl. 271—79)

This invention relates to paper feed guides for use in a sheet material conveyor system.

More specifically, the invention relates to an improved floating feed guide for positioning a sheet of paper relative to a gripper mechanism in a conveyor system and is shown as being utilized in an automatic xerographic reproducing machine.

In the process of xerography, an electrostatic latent image of the copy to be reproduced is formed on a xerographic plate, usually in the form of a rotating drum, and is developed with a toner material to form a powder image of the copy on the drum. The powder image is then transferred to a sheet of support or transfer material, usually paper.

Thus, in some automatic xerographic machines, it is necessary to manually feed a sheet of paper into a conveyor system which carries the paper into contact with the xerographic drum, through a heat fuser and into a discharge tray. The conveyor system contains a sheet paper gripper mechanism which grips the end of the paper as it is inserted into the machine by the operator and draws the paper through the conveyor flow path. At the end of each machine cycle, one of the gripper mechanisms stops at the paper feed-in station in position to receive another sheet of paper and to start another machine cycle. The gripper mechanism is so constructed that the paper must fit uniformly across its length into a slot along the top of the gripper mechanism. If the paper gripper stopped at precisely the correct position, the paper could be fed into the machine and guided by a stationary guide plate into the paper gripper. However, minor variations in the position of the paper gripper results in improper gripping and positioning of the paper as it is fed into the machine. If the gripper does not grip the paper uniformly across its front leading edge then the gripper mechanism may move away without carrying the paper into the machine or it may pull the paper into the machine at an angle and not in proper registration with the xerographic drum or it may cause the paper to jam in the machine resulting in costly and time-consuming repairs.

In order to ensure proper feeding of paper into the gripper mechanism, it is necessary that the paper guide be in alignment with the opening in the top of the gripper mechanism wherever the gripper mechanism stops, within predetermined allowable limits. Although the gripper mechanism does not stop at precisely the same point after each cycle, it does stop in a determinable maximum range of positions. Within this range, the paper feed guide must be self-aligning with the opening in the gripper mechanism.

It is therefore the primary object of this invention to improve sheet feed guide means so that the guide means will be in alignment with a sheet gripper mechanism, wherever the sheet gripper mechanism may stop within a predetermined range.

It is a further object of this invention to improve sheet feed guide means so that the sheet gripper mechanism will align the guide means with the opening in the gripper mechanism.

It is a further object of this invention to improve sheet feed guide means so that an operator may insert a sheet of material into a conveyor system with one simple movement and insure that the sheet of material will be in proper alignment with a sheet gripper mechanism.

2

It is a further object of this invention to improve sheet feed guide means so that they are self-aligning and require no manual adjustment by the operator.

These and other objects of the invention are attained by means of a guide plate that is freely suspended from the frame of the xerographic machine and has an arm in interference relationship with the movement of the sheet gripper mechanism. Thus, as the gripper mechanism approaches the feed-in position, it contacts the guide plate arm and positions the guide plate relative to the opening in the gripper mechanism.

The invention is disclosed in the appended drawings, in which:

FIG. 1 is an isometric view of a type of automatic xerographic reproducing machine in which the present invention is particularly adapted to utilization;

FIG. 2 is an isometric view, with covers partly removed, of a portion of the paper handling mechanism of the machine of FIG. 1;

FIG. 3 is an enlarged isometric view of the paper conveyor system disclosed in FIG. 2, and embodying the present invention;

FIG. 4 is a top view of the gripper mechanism of the machine shown in FIGS. 1, 2 and 3, with the gripper bars in a closed position;

FIG. 5 is an enlarged view of the gripper mechanism shown in FIG. 4, with the gripper bars in a closed position;

FIG. 6 is a rear view of the gripper mechanism of FIG. 4;

FIG. 7 is an enlarged view of the gripper mechanism shown in FIG. 4, with the gripper bars in an open position;

FIG. 8 is a sectional view of the gripper mechanism taken along line 8—8 of FIG. 5;

FIG. 9 is a side view of the paper feed guide mounted on the machine of FIGS. 1 through 3; and

FIG. 10 is another embodiment of the paper feed guide shown in FIG. 9.

The xerographic apparatus comprises a xerographic plate 20 shaped in the form of a rotating cylindrical drum. The xerographic plate includes a photoconductive layer of light receiving surface on a conductive backing and is positioned on a shaft 10 to rotate in the direction indicated by the arrow to cause the drum surface sequentially to pass a plurality of xerographic processing stations.

For the purpose of the present disclosure, several xerographic processing stations in the path of movement upon the surface may be described functionally, as follows:

A charging station A, at which a uniform electrostatic charge is deposited on the photoconductive layer of the xerographic drum;

An exposure station B, at which a light or radiation pattern of the copy to be reproduced is projected onto the drum surface to dissipate the drum charge on the exposed areas thereof, and thereby form a latent electrostatic image of the copy to be reproduced;

A developing station C, at which a xerographic developing material including toner particles having an electrostatic charge opposite to that of the electrostatic latent image are cascaded over the drum surface, whereby the toner particles adhere to the electrostatic image to form a xerographic powder image in the configuration to be reproduced;

A transfer station D, at which the xerographic powder image is electrostatically transferred from the drum surface to a transfer material or support surface; and

A drum cleaning and discharge station E, at which the drum surface is brushed to remove residual toner particles remaining on the drum after image transfer, and at which the drum surface is exposed to a relatively bright

light source to effect substantially complete discharge of any residual electrostatic charge thereon.

At charging station A, there is a corona discharge array 21 of one or more discharge electrodes that extend transversely across the drum surface and are energized from a high potential source. Charging apparatus may be of the type disclosed in Vyverberg Patent No. 2,836,725, issued May 27, 1958.

Next subsequent thereto in the path of motion of the xerographic drum is exposure station B, which contains an optical scanning or projection mechanism generally designated 11. The projector consists of a lamp LMP1, a reflector 12 and a series of lenses 22. A data processing card containing an aperture, and referred to herein as the aperture card, is placed in a carriage, (not shown) between the lamp LMP1 and the lens 22. The aperture in the data processing card contains a microfilm 23 containing an image of a copy to be reproduced. The lamp LMP1 projects the image on the microfilm 23 through lens 22 onto a series of object mirrors which reflect the image onto the surface of the xerographic drum. A viewing plate 3 is provided whereby the image to be flashed on the xerographic drum may be viewed prior to the operation of the machine. The aperture card is arranged in a film holder and a movable carriage which moves in a path traversing the optical path of the lens whereby the subject image of the film is scanned in timed relation to the movement of the light receiving surface of the xerographic drum and a light image corresponding to the subject image is transferred to the surface of the xerographic drum.

Adjacent to the exposure station is a developing station in which there is positioned a housing 31 containing a suitable "two component" developing medium. In this arrangement, a bucket-type conveyor 13 driven by motor MOT5 is used to carry developing material to the upper part of the housing where it is cascaded down onto the xerographic drum.

As the developing material is cascaded over the xerographic drum, toner particles are pulled away from the carrier component of the developing material, by the electrostatic charge on the drum, and form powder images of the copy being reproduced. The carrier components pass off the drum into the lower portion of the housing 31 for recycling. As powder images are formed, additional toner material may be supplied to the developing material in proportion to the amount of toner deposited on the drum surface.

After passing developing station C, the xerographic drum rotates past image transfer station D. At the transfer station, a sheet feeding mechanism is adapted to feed sheets of transfer material, usually paper, successively to the xerographic drum in registration with the formed xerographic powder image on said drum.

In the embodiment shown, the conveyor system includes a pair of chains 14 carrying one or more paper grippers 15 in a circuit between sheet feeding stations 16 and a sheet delivery station 17. Actuating cams 25 (see FIG. 3) are provided to activate the grippers to take hold of the front edge of a sheet of support material at station 16, and to hold the sheet while traveling to the delivery station 17, and there to release the sheet for removal from the machine. The sheet of transfer material is fed manually by an operator to paper gripper 15 and is forwarded by the paper gripper into contact with the xerographic drum at image transfer station D.

The transfer of a xerographic powder image from the drum surface to the support material is effected by means of a corona transfer device 44 located at or immediately after the point of contact of the support material and the xerographic drum. The corona transfer device is substantially similar to the corona discharge device 21 that is employed at charging station A, in that it includes an array of one or more corona discharge electrodes that are energized from a suitable high potential

source and extend transversely across the drum surface. In operation, the electrostatic field created by the corona discharge device is effective to cause the transfer material to electrostatically adhere to the drum surface, whereat the transfer material moves synchronously with the drum surface in contact therewith. The electrostatic field is also effective to attract the toner particles comprising the powder image from the drum surface and causes them to adhere electrostatically to the surface of the transfer material.

As the paper gripper is advanced by the chain conveyor, it strips the sheet of transfer material from the drum and transports it to a fixing device, such as heat fuser 45, where the xerographic powder images previously transferred to the support surface are permanently fixed thereto. A series of suitable support rods 18 are provided to guide the trailing edge of the sheet of support material in proper relation to the heat fuser. The heat fuser 45 contains electrical heating elements which are connected to a suitable source of power (not shown). After fusing, the finished copy is discharged from the apparatus at sheet delivery station 17.

After the image is transferred from the xerographic drum to the support surface, the xerographic drum rotates past cleaning station E to remove any residual charge and developing material that may remain on the xerographic drum. A corona precleaning device 51, similar to corona charging device 21, is positioned to impose an electrostatic charge of suitable polarity on the drum and powder adhering thereto, to aid in effecting removal of the powder from the drum surface. A rotatable brush 52 is positioned to effect removal of this residual powder from the drum and a source of light, such as lamp LMP2 floods the drum surface with light to cause dissipation of any residual electric charge remaining on the drum. Any powder particles removed by brush 52 are collected in tank 56 by means of exhaust blower 57.

The automatic xerographic machine is suitably enclosed in a housing generally designated 1 and contains a control panel designated 2. To operate the machine, the operator would stand facing feed-in station 16 and press the appropriate switch to initiate operation of the machine. A sheet of transfer material is fed into feed-in station 16 initiating operation of the conveyor system and projector mechanism. The projector scans the microfilm 23 and gripper bar 15 grips the sheet of transfer material and draws it into the machine to receive the powder image from the xerographic drum. The feed-in station 16 is more clearly seen in FIG. 2, and contains a suitable counter 9 for use in positioning the sheet of transfer material as it is being entered into the machine, and a guide plate 64 to guide the sheet material into the opening in the gripper mechanism.

Referring now to FIG. 3, the conveyor chains 14 are mounted on parallel pairs of sprockets 46, 47, 48, 49 and 50, which are mounted on side frame members 60 and 61. Each gripper bar 15 is mounted on chains 14 and is carried in a continuous path around each of the sprockets back to the original position. Mounted between the pair of sprockets 50 on a shaft 53 is a paper guide roll 54. Paper guide roll 54 provides a support surface for the sheet of transfer material as it is carried around sprockets 50 by gripper mechanism 15.

Mounted on side frame 60 is a limit switch 4LS which, when activated by an actuator 19 mounted on chain 14, stops the conveyor mechanism so that gripper bar 15 is in position to receive a sheet of transfer material. Limit switches 8LS and 9LS are mounted on side frame 61 and also are activated by actuator 19, mounted on chain 14. These switches 8LS and 9LS control the operation of the projector assembly so that the xerographic image on the drum surface is in timed relation to the movement of the paper conveyor system. A limit switch 5LS is located below guide plate 65 and is positioned to be activated by the leading edge of the sheet of paper in-

serted into the gripper mechanism. The switch 5LS initiates operation of the conveyor drive system.

Although any suitable paper gripper may be used to grip the sheet of transfer material, the paper grippers 15 are of the type disclosed in copending application, Serial No. 46,462, filed concurrently herewith on August 1, 1960, now Patent No. 3,071,370, in the name of Hunt et al.

As shown in detail in FIGS. 4 through 8, inclusive, the paper gripper 15 consists of a gripper bar housing in which a right-hand gripper bar 74 and a left-hand gripper bar 75 are positioned within the housing to coact with a portion of the housing to grip a sheet of transfer material.

The gripper bar housing includes a bottom panel 76 and a top panel 77 held together in spaced parallel relation to each other as by screws 78 threaded into center spacer 81, and end spacers 82 secured as by welding to the bottom panel and top panel, respectively.

The bottom panel which is of a length to extend transversely between the two roller chains has up-turned end extensions 83 with suitable apertures formed therein to coincide with the pitch of the chains whereby the bottom panel is adapted to be attached to the chains 14 by means of elongated chain pins 84 of the roller chains. The bottom panel which is substantially U-shaped has a longitudinal rear lip 85 (in terms of the direction of chain travel) which is of a length greater than the length of the leading edge of a sheet of transfer material on which xerographic powder images are to be transferred.

The bottom panel has an aperture 80 in the center thereof to receive the actuator lever of limit switch 5LS when positioned thereover.

The right-hand gripper bar 74 and the left-hand gripper bar 75 are actuated by means of a right-hand lever 86 and a left-hand lever 87, respectively, each being pivotally secured in the gripper bar housing by a lever pivot pin 88 positioned in suitable apertures in the bottom panel 76 and secured thereto as by silver soldering. Each of the lever pivot pins 88 has a threaded aperture therein to receive a screw 78 passing through the top panel.

The right-hand lever 86 which is pivotally supported near its center by the lever pivot pin 88 on the right-hand side of the gripper assembly is also pivotally secured near one end to the right-hand gripper bar by a dowel pin 91 held in place by the top and bottom panels. The other end of this lever extends beyond the right-hand end of the gripper bar housing and is suitably formed to extend above the up-turned end of the bottom panel whereby it may be actuated by cam 25 to effect movement of the right-hand gripper bar away from the turned-up lip of the bottom panel.

The left-hand lever 87 which is pivotally supported near its center in a similar manner to the right-hand lever by a lever pivot pin 88, is also pivotally secured near one end to the left-hand gripper bar by a second dowel 91. The other end of the left-hand lever extends beyond the left-hand end of the gripper bar housing to be actuated by a cam 25 to effect movement of the left-hand gripper bar away from the turned-up lip of the bottom panel.

The right-hand gripper bar and the left-hand gripper bar cooperate with the lip of the bottom panel to grip a sheet of transfer material inserted therebetween to enable the sheet of transfer material to be transported to the machine, these gripper bars being normally biased toward the lip of the bottom panel by means of a leaf spring 92 having its center portion positioned between the spacer 81 and the front turned-up edge of the bottom panel, one end of the spring contacting the left-hand lever to bias the gripper bars against the lip, or against the lip of the bottom panel with a sheet of transfer material interposed therebetween.

The right-hand lever and the left-hand lever of the gripper bar when actuated by the cams are pivoted around the pivot pins 88 to force the gripper bars toward the front of the gripper bar housing against the tension of spring 92, a pair of stops 93 being positioned to limit the for-

ward travel of the gripper bars. To prevent binding of the gripper bars against the pivot pins, each of the gripper bars is formed with a suitable notch 95 to permit the gripper bar to slide relative to the gripper pins.

As a sheet of paper or transfer material is fed into the xerographic machine at station 16, the front leading edge must be positioned in gripper mechanism 15 between the gripper bars 74 and 75 and the rear lip 85 of bottom panel 76.

As seen in FIGS. 3, 9 and 10, there is a sheet guide assembly 63 fastened to the frame of the xerographic machine at feed-in station 16 and positioned above the stop position of gripper mechanism 15.

The paper guide plate 64 is a flat plate shaped in the form of a V and extending across an opening in frame 1 at feed-in station 16. The leg of the V-shaped guide plate closest to feed-in station 16 extends from above the top of counter 9 downward to a point immediately above the top of the gripper mechanism 15. As a sheet of material is pushed across the top of counter 9, it encounters guide plate 64 and is directed downward into gripper mechanism 15. The other leg of the V-shaped guide plate is attached to brackets 66 by means of pivot pins 67. Brackets 66 are fastened to either the bottom of counter 9, as shown in FIG. 9, or to any frame member, as shown in FIG. 10, and supports the entire guide plate assembly. A positioning rod 68 connects guide locators 65 serving the dual purpose of keeping the guide locators rigid and properly aligned, and also serves as a counterweight to pivot the guide locators 65 around pins 67.

The guide locators 65 have downwardly extending arms 69 in interference relationship with the path of travel of the gripper mechanism. The arms 69 are located at the rear of the guide locators 65 and are spaced from the front of the locators so that the guide plate 65 will be directly over the opening in the gripper mechanism when the gripper mechanism is in contact with the arms 69.

As the gripper mechanism 15 approaches its normal stop position, the leading edge strikes arms 69 of guide locators 65. At this point, the outer sloping surface of guide plate 64 is in line with the slot in the top of the gripper mechanism. As the gripper mechanism travels on to the point where it finally comes to rest, the guide locators carrying the guide plate rotates about pivot pins 67, keeping the sloping surface of the guide plate aligned with the slot opening in the top of the gripper mechanism.

The machine operator slides a sheet of paper or support material along the top of counter 9 until it strikes guide plate 64 at which point the paper is deflected downward along guide plate 64 into the slot in the gripper mechanism. The operator continues to slide the paper forward until a slight buckle in the paper occurs, thus insuring proper seating of the paper in the gripper mechanism. As the paper slides into the gripper mechanism, it trips switch 5LS, which, after a time delay of two seconds, initiates operation of the conveyor system. The two-second time delay permits the operator to adjust and position the paper, if necessary.

As the conveyor system starts moving, the chains 14 carry gripper mechanism 15 away from feed-in station 16. The actuating cams 25 release arms 86 and 87 allowing spring 92 to move the gripper bars 74 and 75 toward the upwardly turned lip 85 of bottom plate 76. Gripper bars 75 and 76 catch the sheet of paper and carry it forward away from the operator. As the gripper mechanism moves forward it pivots the guide locators 65 around pivot pins 67 permitting free passage of the gripper mechanism. The positioning rod 68 swings the guide locators 65 and guide plate 64 downward into position to contact the next gripper mechanism for the next machine cycle.

Although the invention is described as used with a conveyor system of an automatic xerographic reproduction machine, it will be apparent to those skilled in this or related arts, that it may readily be applied to any system in which it is required to handle sheets of material by

means of a conveyor system. Therefore, since changes could be made in the above construction, and different embodiments of this invention could be made without departing from the scope thereof, it is intended that all matter contained in the specification and drawings be interpreted as illustrative and not in a limiting sense.

What is claimed is:

1. In a sheet material conveyor system containing a sheet gripper mechanism, means for guiding individual sheets into the gripper mechanism including a guide plate having a surface transverse to the path of movement of sheet material as it is inserted into the gripper mechanism, and a positioning arm attached to said guide plate and extending into interference relationship with the path of movement of said gripper mechanism, said guide plate and said arm being pivotally mounted so that whenever said arm is in contact with the gripper mechanism the guide plate is immediately above the gripper mechanism and a plane containing the surface of the guide plate extends transversely through the length of the gripper mechanism, whereby sheet material inserted into the conveyor system will be deflected into the gripper mechanism. 15
2. In a sheet material conveyor system including a sheet gripper mechanism containing a flat bar with an opening therein capable of receiving sheet material, and means to retain said material, sheet feed guide means consisting of a flat guide plate the surface of which lies in a plane parallel to the length of said gripper mechanism and in interference relationship to the movement of a sheet of material inserted into said conveyor system, said plate being pivotally mounted at one end above the path of movement of said gripper mechanism and containing an arm extending into interference relationship with the path of movement of said gripper mechanism, said guide plate surface and said arm being spaced in relative position such that whenever said gripper mechanism is in contact with said arm the plane of said guide plate surface passes through said opening in the gripper mechanism. 30 35 40

3. In a sheet material conveyor system containing a sheet gripper mechanism and means to stop said gripper mechanism in a predetermined range of positions, said gripper mechanism including a relatively flat bar member with an opening adapted to receive sheet material and means to grasp said sheet material when inserted in said opening,

the combination of means for guiding individual sheets into the opening in said gripper mechanism consisting of a guide plate containing a flat surface extending parallel to the length of said gripper mechanism and located in interference relationship to the path of travel of the leading edge of sheet material as it is fed into the conveyor system, said guide plate being pivotally mounted above the path of movement of said gripper mechanism so that a plane containing the flat surface of said guide plate passes through the predetermined range of stopping positions of said gripper mechanism, and a positioning member attached at one end to said guide plate and located in interference relationship with the path of movement of said gripper mechanism, the other end of said positioning member being spaced from the end of said guide plate a distance such that when the positioning member is in contact with the leading edge of the gripper mechanism the edge of the guide plate is positioned in line with the opening in the gripper mechanism, whereby sheet material inserted into the conveyor system is deflected downward by the flat surface of the guide plate and into the opening in the gripper mechanism.
